MULTIVANE INTAKE CONTROL VALVE

Clifton M. Chastain and Shirley Johnson, Mineral
Wells, Tex.

Application April 18, 1938, Serial No. 202,777

2 Claims. (Cl. 123—56)

This invention relates to valves for the control of air or fuel into the compression chamber of an internal combustion engine of the two cycle type, and has for the primary object the provision of a multivane type device of this character which will provide a positive control of fuel or air into the compression chamber admitting fuel or air thereto during one stroke of the piston and closing the supply of fuel or air to said compression chamber on the next stroke of the piston so that the latter may transfer the fuel or air from the compression chamber to the firing chamber of the engine for ignition. This valve has a main advantage of permitting fuel or air to pass through the valve housing in the same direction as the direction of rotation of the vanes to prevent undue disturbance of the fuel or air.

With these and other objects in view, this invention consists in certain novel features of construction, combination and arrangement of parts to be hereinafter more fully described and claimed.

For a complete understanding of our invention, reference is to be had to the following description and accompanying drawing, in which

Figure 1 is a fragmentary horizontal sectional view showing a two cycle type of internal combustion engine and opposed cylinders equipped with a control valve constructed in accordance with our invention.

Figure 2 is a view similar to Figure 1 showing the valve closing the source of fuel or air to the compression chamber while the piston is permitting the transfer of the fuel or air under compression from the compression chamber to the firing chamber.

Figure 3 is a horizontal sectional view showing the vanes of the valve positioned as when fuel or air is admitted to the compression chamber.

Figure 4 is a sectional view taken on the line 4—4 of Figure 3.

Referring in detail to the drawing, the numeral 1 indicates a fragmentary portion of an internal combustion engine of a two cycle opposed cylinder type frequently employed for outboard motors wherein the cylinders are indicated by the character 2 connected by a crank case 3, the cylinders having passages 4 connecting the firing chambers of the cylinders with the crank case during certain positions of the pistons 5. The crank shaft is indicated by the character 6 and is connected to the pistons by connecting rods 7 so that the pistons move in unison, that is, the pistons move together on their intake, compression and firing strokes.

The ignition mediums for the cylinders are indicated by the character 8 and the exhaust ports by the character 9. The construction described is common in the type of engine referred to and to which the present invention is adapted. 5

Formed on the crank case 3 is a valve housing 10 having communication with the crank case by a port 11 and is provided with an intake port 12. Integral with the valve housing is a gear housing 13. A shaft 14 is journaled in the housings 10 and 13 and has secured thereto a gear 15 meshing with a gear 16 secured on the crank shaft 6. Secured on the shaft 14 in the valve housing is a rotor 17 including equally spaced radially extending vanes 18 having wiping contact with 15 the walls of the valve housing and adapted to open and close the ports 12 and 11 to each other during the rotation thereof. The gearing between the shaft 14 and the crank shaft is such that the crank shaft makes three complete revolutions to one revolution of the rotor. The timing of the rotor with the pistons is such that the vanes open the ports 12 and 11 to each other during the suction stroke of the pistons 5 and close the ports 12 and 11 during the compression and 25 firing strokes of the pistons. It is to be understood that the port 12 is connected to a fuel source (not shown).

The direction of rotation of the vanes is in the same direction of the path of travel of the 30 fuel from the port 12 to the port 11 through the housing 10 so as not to unduly disturb the fuel.

In operation, during the outward movement or suction strokes of the pistons 5 the vanes 18 are positioned to communicate the ports 12 and 11 so that fuel will be drawn into the crank case and as the pistons complete their suction strokes or reach their outermost positions, the vanes close the ports 12 and 11 to each other and maintain said ports closed to each other 40 during the working or firing strokes of the pistons or until said pistons reach their innermost positions with respect to the crank shaft. During the initial movement of the pistons towards the crank shaft the fuel is compressed in the 45 crank case and as the pistons complete their inward movement or compression strokes, the pistons open the compression chamber to the firing chamber as well as the exhaust ports 9 so that on the next outward movement of the 50 pistons the fuel received from the crank case under compression is further compressed in the firing chambers and fired by the ignition medium on the pistons reaching their outermost positions with respect to the crank shaft. 55

What is claimed is:

1. The combination with an internal combustion engine of the type having a crankcase directly communicative with cylinders positioned at diametrically opposed sides thereof, said cylinders having hollow pistons reciprocally mounted therein, said pistons having piston rods pivotally connected thereto and to a crankshaft disposed within said crankcase, said cylinders having fuel passages exteriorly thereof opening through the cylinder walls at spaced points therealong in a manner whereby the upper ends will open into the cylinders above the said pistons and the lower ends of the said passages will open into the cylinders through an aligning port in the piston walls when the said pistons have completed their power stroke, the ports in the said pistons being adapted to move out of engagement with the openings of the fuel passage during their compression stroke; of a cylindrical housing formed exteriorly of the crankcase, said housing being entirely enclosed except for an outlet port communicating with the crankcase and an inlet port disposed at right angles to the said outlet port and communicating with a source of fuel supply; a valve member axially mounted for rotation within said housing, said valve having three equi-spaced radial vanes having a wiping contact with the inner wall of the housing; and means to rotate said valve member in a manner whereby adjacent vanes will permit direct communication between the inlet and outlet ports at preselected intervals and close communication therebetween at other preselected intervals.
2. The combination with an internal combustion engine of the type having a crankcase di-

rectly communicative with cylinders positioned at diametrically opposed sides thereof, said cylinders having hollow pistons reciprocally mounted therein, said pistons having piston rods pivotally connected thereto and to a crankshaft disposed within said crankcase, said cylinders having fuel passages exteriorly thereof opening through the cylinder walls at spaced points therealong in a manner whereby the upper ends of the fuel passages will open into the cylinder 10 above the said pistons and the lower ends of the said passages will open into the cylinders through aligning ports in the piston walls when the said pistons have completed their power stroke, the ports in the said pistons being adapted to move 15 out of engagement with the openings of the fuel passage during their compression stroke; of a cylindrical housing formed exteriorly of the crankcase, said housing being entirely enclosed except for an outlet port communicating with 20 the crankcase and an inlet port disposed at right angles to the said outlet port and communicating with a source of fuel supply; and a valve member rotatably mounted within said housing, said valve including three equi-spaced 25 radial vanes the ends of which wipedly engage the inner wall of the housing, adjacent pairs of said vanes being adapted to straddle the said inlet and outlet ports during the suction stroke of the pistons of the said engine to permit passage of fuel through the housing and to close communication between the said inlet and outlet ports during the compression and firing stroke 30 of the pistons.
